US0D1102484S

(12) **United States Design Patent** (10) Patent No.: **US D1,102,484 S**
(45) Date of Patent: ** Nov. 18, 2025

(54) **CENTRIFUGAL COMPRESSOR**

(71) Applicant: **FUJIAN SNOWMAN COMPRESSOR CO., LTD**, Fuzhou (CN)

(72) Inventors: **Yunzhen Lin**, Fuzhou (CN); **Guohui Zhou**, Fuzhou (CN); **Xinzhu Chen**, Fuzhou (CN)

(73) Assignee: **FUJIAN SNOWMAN COMPRESSOR CO., LTD**, Fuzhou (CN)

(**) Term: **15 Years**

(21) Appl. No.: **29/920,126**

(22) Filed: **Dec. 8, 2023**

(30) **Foreign Application Priority Data**

Sep. 27, 2023 (CN) 202330632376.4

(51) LOC (15) Cl. **15-02**

(52) U.S. Cl.

USPC **D15/9**

(57) **CLAIM**

The ornamental design for a centrifugal compressor as shown and described.

DESCRIPTION

FIG. 1 is a perspective view of a centrifugal compressor showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the centrifugal compressor that form no part of the claimed design.

1 Claim, 8 Drawing Sheets
